UNITED STATES PATENT OFFICE.

EDWARD SCHRANTZ, OF WARRENTON, MISSOURI.

RAIL-TONGS.

SPECIFICATION forming part of Letters Patent No. 554,461, dated February 11, 1896.

Application filed November 6, 1895. Serial No. 568,103. (No model.)

To all whom it may concern:

Be it known that I, EDWARD SCHRANTZ, a citizen of the United States, residing at Warrenton, county of Warren, State of Missouri, have invented a certain new and useful Improvement in Rail-Tongs, of which the following is a full, clear, and exact description, reference being had to the accompanying drawings, forming part of the specification, where-

10 in—

Figure 1 is a perspective view of my improved rail-tongs as applied to a rail. Fig. 2 is a side elevational view of the same, one of the jaws being removed to more clearly show 15 the manner of pivotally connecting the several members. Fig. 3 is a detail view of one of the members of which the tongs is composed, and Fig. 4 is a detail view of the other tongs member.

20 This invention relates to a new and useful improvement in rail-tongs of that class which are specially adapted for use in connection with railroad-rails.

The features of this invention reside in 25 slotting one member of the tongs, which slot is enlarged at one end, said slot receiving the pivot-pin located in a bifurcation of the other member, whereby the jaws may be separated without depressing the handles, and when the 30 tongs are carrying a load the pivot-pin will seat itself in said enlargement, preventing displacement of the fulcrum.

The invention further contemplates, in addition to the above, forming the handles with 35 a vertical and horizontal portion, which horizontal portion is on a plane above the plane of the body portion of the tongs, in pivotally securing a link to one of said members near the upper end of the vertical portion of its 40 handle, and in arranging a hook or projection correspondingly located on the other member, with which said link is adapted to engage to prevent the handles from falling when the jaws are grasping an article.

45 The invention further consists in the construction, arrangement, and combination of the several parts, all as will hereinafter be described and afterward pointed out in the claims.

50 In the drawings, A and B indicate the two handles which extend from the respective members of the tongs, said handles being

bent down at an angle, as at a and b, respectively, to the tongs proper, whose bodies C and D are on substantially a horizontal plane. 55

The jaws E and F of the tongs are located below the line of the bodies and are preferably staggered in relation to each other, so that the jaws bear at three points on the rail. This is accomplished by bifurcating one of 60 the bodies C, as at c, in which bifurcation is received the body D of the other tongs member. This member D is slotted, as at d, to receive the pivot-pin G, whose ends are mounted in the body C. The inner end of this slot is 65 enlarged, as at d', said enlargement making the slot of substantially a T or keyhole form, which affords a seat for the pin G to one side of the slot proper. By this construction when it is desired to grasp a rail the body D is telescoped within the bifurcation of body C, the slot permitting this, and the jaws are in this manner separated without requiring the handles to be depressed. When the jaws are in 70 position to grasp the head of the rail, they are brought together, as shown, when the pin G will be seated in the enlargement of the slot, preventing displacement of the fulcrum during the time the rail is being lifted. The upward pressure of the handles will tend to force 75 the jaws more closely together and the pin will rest in the lower portion of the enlargement of the slot, preventing dislocation of the jaws while the rail is suspended by the tongs or while there is any weight at all on 80 the jaws.

To prevent the handles from falling out of position and the consequent displacement of the jaws from the rail, I secure them together above the pivotal point by some suitable 90 means, said means being shown in the drawings as consisting of a link H, pivoted in one of the handles near the upper end of the vertical portion, said link engaging a suitable projection in the form of a nose h arranged 95 on the other handle. In this manner when the tongs are not in use they will retain their proper position by reason of the link connection above the pivotal point, and when said tongs are grasped the weight of the handles 100 will tend to slightly elevate the jaws, in which event the pin will rest in the upper portion of the enlargement of the slot.

I am aware that many minor changes in

construction, arrangement, and combination of the several parts of my device can be made and substituted for those herein shown and described without in the least departing from the nature and principle of my invention.

Having thus described my invention, what I claim, and desire to secure by Letters Patent, is—

1. A rail-tongs, comprising two members, one of said members carrying the pivot-pin and the other of said members being formed with a slot to receive said pin, said slot being somewhat enlarged at one end; substantially as described.

2. A rail-tongs, comprising two members which are slidingly and pivotally connected together, the handles of said members having

a vertical portion and a horizontal portion, said horizontal portion being on a plane above the plane of the body portion of the tongs, and a link pivotally secured to one of said members near the upper end of the vertical portion of its handle, and a hook or projection correspondingly located on the other member and with which said link is adapted to engage; substantially as described.

In testimony whereof I hereunto affix my signature, in presence of two witnesses, this 14th day of October, 1895.

EDWARD SCHRANTZ.
